(57) CLAIM

The ornamental design for a shawl and lap blanket, as shown and described.

DESCRIPTION

FIG. 1 is a perspective view of the shawl and lap blanket of the present invention with a person wearing the garment shown in dashed lines with arms straight down.

FIG. 2 is a perspective view of the shawl and lap blanket of the present invention with a person wearing the garment shown in dashed lines with forearms elevated.

FIG. 3 is a front view.

FIG. 4 is a rear view.

FIG. 5 is a left side view.

FIG. 6 is a right side view.

FIG. 7 is a top view; and,

FIG. 8 is a bottom view.

The broken line showing the body of a wearer is for illustrative purposes only and forms no part of the claimed design.
